LIDDED BEER MUG

John R. Christensen, P.O. Box 2382,
Green Bay, Wis. 54301

Filed July 22, 1968, Ser. No. 12,845

Term of patent 14 years

Int. Cl. D7—01

U.S. Cl. D44—9

FIG. 1

FIG. 3

FIG. 1 is a front elevational view of a lidded beer mug showing my new design;

FIG. 2 is a right side elevational view; and

FIG. 3 is a top plan view.

I claim:

The ornamental design for a lidded beer mug, as shown.
